ELEVATOR SIGNALING SYSTEM

Robert H. Gaylord, Los Angeles, Calif.

Application April 6, 1932, Serial No. 603,459

9 Claims. (Cl. 177—336)

This invention relates to an improvement on the type of elevator signaling system as disclosed in the patent issued to James B. Smalley and Charles A. Reiners, No. 826,752, dated July 24, 1908, and one of the main objects of this invention is to provide in connection with such an elevator signal system, improved means for controlling the floor or landing signals, and also the elevator operator's signals so that but one landing signal and one car operator's signal will be operated at any one time at or for a floor, in an installation of a plurality of elevators which at the time are in the same direction of travel.

A further object of the invention is to provide for control of the respective signal circuits in such manner that the operation of any signal circuit to produce a signal will automatically disable all other signal-circuits of the associated group, so that only one signal can be given at any one time, and a special object of the invention in this connection is to provide for such intercontrol of the circuits without the use of mechanical interlocking means. In this connection an important feature of this invention is the means used by which the aforesaid signaling or indicating means are controlled. The device for controlling the indicating or signaling means being associated electromagnetically in their dependency for operation, with the elimination of any mechanical interconnection for controlling their operation, this feature makes it practical to remotely separate the devices associated or functioning together, as they are only electrically interconnected.

Another important feature is that on the functioning of a device to establish a signal circuit all other devices associated therewith will function to open a break in their respective signal circuits thereby eliminating the possibility of duplicate signals. An important feature is that the devices, in their normal routine operation, are not called upon to break or make circuits except in cases where an operator wishes to transfer a signal to another car.

The elimination of the necessity of continually making and breaking the actual current within the device, except occasionally, permits of simple construction of the devices and assures long life of the circuit closing means and contact points associated with the device.

Another feature of the present invention is that the normal position of the devices is such that the breaks controlled thereby in the signal circuits are normally closed, and therefore are

always receptive to function in the establishing of signal circuit connections.

Another important feature is the simplicity with which this improvement may be applied to installations already in use and its satisfactory operation on direct or alternating current.

An important advantage of the system herein-after described is the small amount of electrical energy required to operate the devices, which permits of their introduction in the signal circuits without impairing the efficiency of the signaling means to any appreciable extent.

The accompanying drawings illustrate apparatus and circuits suitable for carrying out my invention and referring thereto:

Figure 1 is a diagram of the circuit connections for two elevators provided with both landing and car signals;

Fig. 2 is a side elevation of the signal setting and resetting device;

Fig. 3 is a side elevation of a set of intercontrolling electromagnetic devices;

Fig. 4 is a plan view thereof;

Fig. 5 is a longitudinal section of the car operated switch or commutator;

Fig. 6 is a section on line 6—6 in Fig. 5;

Fig. 7 is a section on line 7—7 in Fig. 5;

Fig. 8 is a section on line 8—8 in Fig. 6;

Fig. 9 is a diagrammatic representation of the winding and connections of the set of intercontrolling devices shown in Fig. 2;

Figs. 10 to 13 inclusive are side elevations of modified forms of inter-control electromagnetic devices;

Fig. 14 is a plan view and Fig. 15 is a side elevation of another modification of the intercontrol electromagnetic devices;

Figs. 16 and 17 are diagrammatic representations of modified methods of winding and connecting a set of intercontrolling devices;

Fig. 18 is a diagrammatic representation of a set of electro-thermal intercontrolling devices; and

Fig. 19 is a diagram of circuit connections for two elevators provided only with landing signals.

This application is a continuation in part of my copending application Serial No. 700,604 filed March 20, 1924.

In Fig. 1 of the drawings I have illustrated diagrammatically the contacts for the controlled switches or commutators for two elevators. The construction and operation of said switches is identical with the construction and operation of the commutator shown and disclosed in said Smalley and Reiners patent, the switches or

commutators being, however, indicated in the drawings as adapted for five story or five landing signal system in place of seven landings as shown in the Smalley and Reiners patent.

5 In Fig. 1 there has been omitted from the diagram most of those contact plates which form no part of the electrical features in order to simplify the same. In this diagram 1 is a source of electricity—such, for example, as an ordinary 10 dynamo. 2 and 3 are elevator cars which are adapted to travel up and down in their respective shafts, and 4 is an electrically controlled signal carried by each car and which is preferably in the form of an electric lamp. Electrically controlled signals located along the elevator shaft 15 may also be provided for signaling the intending passenger that a certain elevator car is approaching him in the direction which he desires to go. These signals are also preferably electric lamps 20 and are indicated at 5 to 12, the top and bottom floors each being provided with a single lamp for each elevator, and each of the intermediate floors with a pair of lamps for each elevator, such as 8 and 9 for the third floor. These will be usually 25 located outside of the elevator shaft adjacent to each doorway, as is common at the present time, one of said lamps serving to indicate a downwardly moving car and the other one an upwardly moving car. There is also provided suitable hand 30 operated mechanism located at each floor, such as ordinary push buttons, by which the intending passenger may control part of any signal circuit so that by pushing one of said buttons he will close or cause to be closed a break in the said 35 signal circuit, so that when the commutator closes the other break in such circuit the signal will be given. These push buttons are indicated at 14 to 21, two of them being located at each floor, except the top and bottom floors, the upper ones 40 being to signal upwardly moving cars, and the lower ones downwardly moving cars. Each push button has a contact connected to one side of a battery 13 and a contact member connected to one of the setting magnets hereinafter set forth, 45 the other side of each setting magnet being connected to the other side of the battery 13. Two cars with corresponding floor signals and commutators are shown in Fig. 1, but it will be evident that the system may be adapted for any 50 desired number of shafts, and that the same may be cross-wired, so that one set of push buttons will control the circuits for all the cars of that bank, as is common in this art. It is not thought necessary to illustrate this duplication and 55 cross-connection in the drawings, as the same will be evident to any person skilled in this art. A car operated switch or commutator is provided for each elevator shaft and is operated by connection with the corresponding cars. The commutator is adapted to determine the time when 60 the signal shall be operated—that is, when the lights may be lighted up, provided that a push-button has been pushed to close the other normally open break in the signal circuit. Each commutator consists of suitably fixed and relatively movable contacts and in the present embodiment the brushes are indicated as constituting the moving members thereof, said brushes being arranged in two groups respectively corresponding to up and down travel of the car and 65 adapted to contact respectively and alternatively with two groups of fixed contacts. Furthermore each of said commutators comprises a moving member or brush carrier 22 (see Figs. 5 and 6) 70 adapted to be moved back and forth by operation 75

of the corresponding car, said moving member, for example, comprising a nut 23, which is adapted to work on a screw shaft 24 operated by connection with the car operating means, and suitable means are provided for tilting said moving member on said shaft to shift the brush carrier so that one group of brushes is operatively engaged with the corresponding fixed contacts while the elevator car is travelling upwardly and to shift the brush carrying means so as to cause 10 the other group of brushes to operatively contact with the other corresponding group of fixed contacts during the downward travel of the elevator car. The means for reversing the movement of the brush carrier may consist of a frictional bearing means as shown at 35 in Fig. 8, whereby the nut 23 is caused to tend to turn one way or the other, in correspondence with the reversal of motion of screw shaft 24, and a guide member 36 15 adapted to engage an arm 23' on nut 23 to hold 20 the brush carrier to one side while it is travelling in one direction and to the other side while it is travelling in the opposite direction, all as set forth in the patent to Smalley and Reiners above 25 referred to. The circuit connections are also controlled by mercury pots and restoring and setting magnets, which have been shown in Fig. 1 adjacent the commutator to more clearly indicate their relation; but they may be placed wherever convenient, and, in fact, are usually placed upon 30 a separate support by themselves, being suitably wired from each separate commutator of the bank of elevators, as indicated in Fig. 1.

The group of fixed contacts for the "down" signal control, in the commutator for each elevator, comprises two series of contact plates, but they need not necessarily be of the form shown in all cases. One such series is indicated at 25 to 27 and the other series at 28 to 30. These two series above indicated are for the car as it moves 40 downwardly, and it will be observed that each plate of the series 25 to 27 has connected with it a "down" light—that is lamp 6 is connected to plate 25, lamp 8 to plate 26, etc. The plates 28 to 30 are connected to switches (indicated as 45 mercury pots 31 to 33 having pivoted contact arms 34) the connections including interlocking electro-magnetic devices hereinafter described. Said pivoted arms 34 for mercury pots 31 to 33 are operated by the setting magnets 38 to 40 controlled 50 by the respective "down" push buttons 15, 17, etc., and said pivoted arms are all connected to one side of dynamo 1. Each setting magnet has an armature 41 (see Fig. 2) controlling the pivoted contact arm 34. The pivoted arm 34 of each 55 switch is normally out of contact with the mercury, and therefore causes a break in the signal circuit, and it and the mercury pot constitute a switch. It will be obvious that there is no limitation to this form of switch, but this mercury 60 pot and pivoted lever construction is a convenient one to use, as has been found by actual practice. The pivoted lever may be caused to drop into the body by different mechanism, but it has been found that a magnet controlled by a floor push 65 button is a convenient and effective means to this end. In the present instance there is provided a setting magnet, such as 38 to 40 (see Fig. 1) connected to a corresponding push button, so that when a button, such as 15, is pushed it will close 70 a circuit from battery 13 through the corresponding setting magnet 38, thereby attracting its armature 41 and releasing the lever 34, which will drop into the pot, as indicated in the diagram. There is also provided a restoring magnet, such as 75

indicated at 43 to 45, for each arm 34 for restoring the same to the normal position shown in Fig. 2 after the car starts to move away from the floor for which the signal has been given. This will be described more in detail hereinafter. It will be observed from the above that each of the intermediate floors is served by one of said floor signals, such as 6, a plate, such as 25, of the series connected therewith, and a plate, such as 28, of the other series which is connected to the source of supply through a switch, which is individually controlled as hereinafter described by hand operated mechanism, such as push button 15, located at said floor at which the signal 6 is also located.

In order to make electrical connection between plates 25 and 28, etc., there is provided a brush or brushes for each series of plates, these brushes, indicated at 47 and 48 being electrically connected as indicated. It will be obvious that when any one pair of these brushes 47 and 48, touch plates 25 and 28, respectively, the floor lamp 6 will be lighted up, providing all other breaks in the circuit having previously been closed, as the third normally open break in the circuit (between plates 25 and 28) will then be closed and this break will remain closed so long as any pair of brushes connects these plates. It is preferred to provide several pairs of these brushes as indicated at 47 and 48, and space the pairs a distance apart less than the width of any single plate of the series, so that the plates 25 and 28, for example, will be electrically connected while the car is moving for several floors, so that the floor light will light up several floors in advance of the car and remain lighted until the car reaches the floor. This relative arrangement is shown in the diagram and will be referred to hereinafter when the particular construction of the brush carrier is discussed hereinafter. It will be observed that the circuit from the dynamo passes through the car-light 4 and then to the long contact strip 55, and there is provided one or more pairs of brushes 56 and 57, connected as indicated, the brush 56 rubbing over strip 55 and the brush 57 making contact with the series 28 to 30. It is preferred to provide the long strip 55 and the brush 56, rather than to attach the circuit from the car lamp directly to brush 57; but the construction shown may not be necessary in all cases. The car signal is therefore in circuit with a brush—in this instance brush 57—on the series of contacts 28 to 30. In the present embodiment this brush 57 is a separate brush from any one of the brushes aforesaid, and this is the construction that is preferred, but it will be observed (see Fig. 1) that when these brushes are in the position shown in that figure the brush 57 rests upon the same plate as the brush 48, and at that time said two brushes 57 and 48 are, in effect, a single brush. In order to light up the car light only a floor or so before the car reaches the floor, brushes 56 and 57 are located behind the brushes 47 and 48, so that the floor light will be lighted up before the car light is lighted. There has also been provided another pair of connected brushes, 56 and 57, so that the car light may be lighted up slightly more than one floor away from the floor at which the car is to stop. Also there has been provided a series of restoring mechanisms for automatically restoring the circuits to normal condition after the car has passed by, in this instance raising the mercury pot arm out of the mercury. Such a series of restoring mechanisms is shown by the restoring magnets 43 to 45, which are all the same as magnets 48 of Fig. 2. It will be observed that, for example,

restoring magnet 43 (see Fig. 2) when energized will raise the lever 34 and drop the right end of the same underneath the end of armature 41, where it will be held until the setting magnet 33 is again energized. In order to energize the restoring magnets at the proper time, there are provided a series of contacts 63 to 65 upon the commutator and a brush 66 adapted to ride on said contacts and suitably connected to the battery 13, in this instance by being electrically connected to a brush 61, rubbing over contact strip 68, so that when the car starts to move away from the floor on which the signal has been given, brush 66 will engage contact 63, say, and energize magnet 43 to break the signal circuit at the mercury pot.

The brushes have been shown in Fig. 1 in the relative positions they occupy as the car is descending, these brushes controlling the signals to a down-moving car. The brushes are omitted from that part of the commutator corresponding to an upwardly moving car as they are not in operation at this time, being out of contact with the plates 10 to 80 on the up side corresponding to the aforesaid plates 25, etc., on the down side. When the car moves upwardly, the brushes for the up contact plates are shifted into a position by means operated by the car, as shown in said Smalley and Reiners patent, so as to make suitable connections for the control of the up signals, so as to operate the up signals and the signal in the car and the up restoring magnets. This shifting of the brushes will be referred to hereinafter. 86 to 88 represent a set of setting magnets, and 90 to 92 a set of restoring magnets for the up side, these magnets being controlled in the same manner as above set forth. Corresponding mercury cups or switches 81 to 83 are also provided. The system is therefore provided with means for controlling the signals when the car is moving up, substantially the same as those heretofore described for use when the car is moving down. 94 is "a night signal" or bell which operates only when the normally closed switch 84 is open.

The above described construction and arrangement of parts is substantially the same as described and illustrated in the patent to Smalley and Reiners aforesaid, with the exception of the electrically operated interlocking means which are, according to my present invention, incorporated in the connections for the floor landing and car signals in place of direct connection of the floor landing signals through the car operated switch to the mercury pots as set forth in said Smalley and Reiners patent. One form of electromagnetic interlocking means constituting the main feature of the present invention as applied to the control of the landing signals is shown more fully in Figs. 3 and 4, each interlocking means comprising a plurality of controlling electromagnets 95, said magnets being shown as mounted adjacent one another, this however not being necessary in the form of the invention shown in these figures. Each magnet controls an armature 96 carrying or attached to a pivotal arm 97 controlling a circuit breaker, said arm 97, for example, cooperating with a mercury pot 98 to control a branch circuit as hereinafter described. Each electromagnet 95 may comprise two coils or windings 100 and 101 which in the form shown in Figs. 3 and 4 are wound on the same core, and are connected in such a manner that when energized they act in opposition. In practice the two windings each extend the entire length of the electromagnet but for the sake

of clearness the windings are shown as separate in Fig. 1. There are two series of sets of the controlling electromagnets 95, one series to control the up signals and the other series to control the down signals and in each series the number of sets is one less than the number of floors provided with landing signals. In the illustrations shown in the drawings there is provided two elevators and each set of controlling electromagnets therefore includes two such electromagnets. Coils 100 for the respective electromagnets 95 of a given set are connected in series, a connection 102 leading from one of said coils to the corresponding mercury pot of the series 31 to 33 and 81 to 83 controlled by a corresponding setting magnet and connections 104 leading from the coil at the other end of the electromagnets 95 of said set to the several coils 101 of the electromagnets 95 in that set in parallel connection. From each coil 101 connection 106 leads to the arm 97 aforesaid which establishes a contact with mercury pot 98 and thence to the wire 107 leading to the corresponding contact of the series 28 to 30 and 13 to 15 of the corresponding car controlled switch.

I prefer to provide in connection with the above described system a car operator's switch 108 for controlling the signal circuits and a car operator's switch 109 for controlling the restoring circuit, each of cars 2 and 3 being provided with a set of said switches 103 and 109 as well as with a car signal 4. The signal operating circuit may be traced as follows.

From the dynamo 1 a wire 110 leads to branch wires 111 and 112, wire 111 being connected to the contact arms 34 controlled by the respective setting magnets 33 etc., for the down operation and wire 112 being similarly connected to the circuit closers controlled by the setting magnets for the up operation. From each mercury pot or contact cooperating with the circuit closer 34 aforesaid a wire 102 leads to a corresponding set of intercontrolling electromagnets 95, wires 107 lead from the mercury pots or contacts 98 of the respective intercontrolling electromagnets for the down operation to the corresponding contacts 28, 29, etc., at the down side of the car operating switch. Similar connections 102 and 107 are provided for the intercontrolling electromagnets for the up operation. From the contacts 25, 26 etc., of the car operated switch wires 114 lead to the respective down signals 6, 8, etc., and similar wires 115 lead from the respective contacts 71 and 72, etc., to the respective up signals 7, 9, etc. From said signals return connections 116 and 117 lead to transfer switch 108 in the car from which a connection 119 leads back to the dynamo. From the long contact 55 of the car operated switch wires 120 and 121 lead to a wire 122 which is connected to the car signal 4, the other side of said car signal being connected together with wire 117 to one side of the transfer switch 108 in the car so that by operating said transfer switch the return circuit for both the car signal and landing signals is interrupted. Similarly the long contact 76 at the upper side of the car operated switch is connected by wire 123 to the wire 121 from which the car signal circuit is completed as above described.

The controlling circuit leads by wire 124, connected to one side of the battery 13, and wire 125, to the several setting magnets 38, 39, etc., from which wires 126 lead to the respective down circuit closers 15, 17, etc., the return circuits for

said circuit closers being established by connections 127 and 128 to the other side of the battery 13. Similar connections 129 and 130 lead from the wire 124 to the respective setting magnets and to the up circuit closers 16, 18, etc., from which the return circuits are completed by the wires 127 and 128 aforesaid.

The restoring circuit leads from wire 124 aforesaid through wire 134 to the respective restoring magnets 43, 44, etc., and thence by wires 135 to respective restoring contacts 63, 64, etc., and from the long restoring contacts 68 the wires 136, 137 and 138 lead to the restoring circuit transfer switch 109 in the corresponding elevator car from which a wire 140 leads to the wire 138 aforesaid connected to the other side of the battery. Opening of transfer switch 109 therefore operates to break the restoring circuit and retain in operative position any circuit closer, 34, which has been operated.

In normal or inactive condition assuming that all the landing circuit closers are open the respective intercontrolling electromagnets 95 are de-energized and the armatures thereof allow the contact members 97 to close connections at 25 the mercury cups or contacts 98, it being understood however that the connections so closed do not establish a circuit since such establishment requires closure of a signal circuit by mercury cup or contact controlled by a setting magnet 30 under the control of a landing switch and also closure of a connection at the car operated switch. Assuming now that down push button 15 on the second floor is closed, the corresponding setting magnet 38 is operated to close circuit at 35

31. The first descending car which enters the signal zone for that floor, for example, car 2 will then cause the signal circuit to be closed by a pair of brushes 47 and 48 between contacts 25 and 28. Current will then flow from dynamo 1 through wires 110 and 111 to arm 34 and contact 31, thence by a wire 102 to the set of interlocking intercontrolling magnets 95 corresponding to the second floor on the down side. The electric current passes first through the two coils 100 of this set of electromagnets in series and then passes through connection 104 to the other winding 101 of the electromagnet of said set which corresponds to the car which is for the time being controlling the signal. From said winding 101 the current passes through the connection 106 to arm 97 and mercury cup or contact 98 and thence by the corresponding wire 107 to the contact 28 of the car operated switch. From contact 25 of said switch the circuit is continued through a wire 114 to the down landing signal 6 at the second floor corresponding to car 2 and thence by wires 116 and 117 to car transfer switch 108 and from said switch by wire 119 to the other side of dynamo or source 60 of current 1. Inasmuch as the two windings 100 and 101 of the said electromagnets 95 are wound oppositely the armature for the magnet corresponding to the car in control is not affected and the contact at 97 and 98 remains closed 65 so that the corresponding down landing signal at the second floor is operated but in the case of the other electromagnet 95 of the same set (being the electromagnet shown at the right on the down side in Fig. 1) only the coil 100 is energized, there being no connection established to the coil 101, so that the armature of said magnet is attracted and the corresponding circuit is interrupted at 97 and 98 so as to open another break in the circuit of the landing signal on 70 75

the second floor corresponding to the other car (or cars) so that no other "down" landing signal can be operated at the second floor until car 2 has relinquished control. Thus it will be seen that in any set of intercontrolling electromagnets or devices the first device to operate renders inoperative the other devices of the set and the signals controlled thereby by interrupting or disabling the operating circuits therefor.

In case the circuits of the differential relay switches (35, 97, 93) for two or more cars, for the same floor should be simultaneously completed, which will occur if two or more cars both travelling in the same direction are within the signaling zone for that floor when the push button for that floor and direction of travel is operated by an intending passenger, and which might also, although very rarely, occur if two or more cars travelling in the same direction should, in exact coincidence, approach said floor after the push button has already been operated by an intended passenger the system is still entirely operative to accomplish the objects of this invention.

Referring particularly to Fig. 9 wherein are shown the differential relay switches and the corresponding commutator segments 12 and 75 for two cars for the same floor, it may be seen, that under these circumstances, the two pairs of contact segments 12 and 75 for both of these cars, will be electrically connected by corresponding brushes (not shown in this figure).

Current will flow from the corresponding contact member 83 through the wire 102 and through the first windings 100 of both of the relays in series in the same manner as described above for the case when only one car was assumed to be in the signal zone.

In the present instance, however, the current will then divide and follow two parallel paths, one of which leads through the other winding 101 of the lower relay in Fig. 9 and thence through the lower contact arm 97, mercury pot 98, wire 107 and the left hand pair of contacts 72 and 75 to the signal for car No. 1 and the other of which leads through branch wire 104 to the other winding 101 of the upper relay and thence through the upper contact arm 97, mercury pot 98, and wire 107 to the right hand pair of contact segments, and thus to the signal for car No. 2. It may be seen therefore, that the full current required for operation of the signals for both cars will pass through the first winding 100 of each of the relays while the current required for only one of these signals will pass through the other winding 101 of each of said relays, due to the fact that the windings 100 are connected in series while the windings 101 are connected in parallel. To illustrate for a specific case, assume that each of said signals consists of a lamp drawing a current of .5 amp., there will in that case be a current of 1 amp. flowing through the first winding 100 of the lower relay and of the upper relay, and a current of only .5 amp. through the other winding 101 of each of said relays. Since the two windings 100 and 101 of each relay are substantially equal and opposite to one another, the net magnetizing effect will be the same as though a current of .5 amp. were passed through only the first winding 100 of each of said relays and each of said relays will, therefore be momentarily magnetically energized and will momentarily tend to move its contact arm 97 to open position.

However, even if the differential relays with

their associated contact arms 97 and mercury pots 98 are substantially similar within manufacturing limits, it has been found by actual experience that due to unavoidable slight differences in speed of operation of the contact arms 97 by the respective electro-magnets or to slight differences in the contact arms or mercury pots themselves, no two of these can be made to operate to break or make connection at exactly the same instant. If one of said contact arms, for example, the arm corresponding to the upper relay lifts sufficiently to break connection with its mercury pot even a fraction of a second in advance of the other arm, as will almost inevitably be the case, the circuit for the signal 15 of car No. 2, for example, will be immediately interrupted and the conditions of current flow in the two relays will immediately be the same as described above for the case when only car No. 1 was in the signal zone, that is to say, the current 20 for operation of the signal of car No. 1 will flow through the first windings 100 of both relays and then through the other winding 101 of only the lower relay, and if this readjustment of current flow occurs before the contact arm 97 for the 25 lower relay has broken connection with its mercury pot 98, this latter contact arm will remain in closed position due to balancing of the current flow in the two windings of the lower relay while the contact arm of the upper relay 30 will be held in open position due to passage of current through only the winding 100 of said relay.

In case there is insufficient difference in rapidity of operation of the two contact arms for such readjustment to occur upon the first movement of said arms toward open position, both of said contact arms will be momentarily opened whereupon current flow will momentarily cease in the 35 signal circuits for both cars.

Such cessation of current flow, however, would cause all of the relays to be completely deenergized and all of the contact arms to immediately return toward their normal or closed position. During this return movement again, one or the other of the contact arms may establish its connection with the corresponding mercury pot sufficiently in advance of the other contact arm to establish its own signal circuit and cause energization of winding 100 of the other relay before 40 said other contact arm reaches closed position, and in that case also the system would operate to leave the first contact arm in closed position and hold the other contact arm in open position.

If the readjustment does not occur on this return movement and both of the contact arms succeed in again momentarily establishing their respective circuits, they will again both tend to move to open position, but after one or two of these repeated opening and closing movements of the contact arms, one of said arms will inevitably gain upon the other during the closing movement, or lag behind the other during the opening movement sufficiently to gain exclusive control of its signal circuit and cause the other contact arm to be held in open position. Under these circumstances the contact arms may be theoretically considered as fluttering momentarily between closed and open position, but it is practically impossible to so design two relays with their corresponding contact arms and mercury pots as to prevent one from gaining on the other in the manner above described and thus cause the signal to be restricted to one or the other of the cars and cause the signal circuits for the other car or 55 60 65 70 75

cars to remain open and the entire time required for any such fluttering action as may occur is in any event only a small fraction of a second. As a result even under the above conditions the signal is given for only one car and no visible operation of the signal for the other car is produced.

If desired in order to further insure correct operation of this system the differential relays may be positively constructed to have relatively different speeds of operation. Thus the differential relays may be constructed so that for any series of them each relay in the series will have a different number of turns of wire thereon with relation to the next relay in the series insuring different speeds of operation thereof if simultaneously energized. This same result may be secured in other way by graduating the weights of the relay arms 96—97 or by any other equivalent ways apparent to those skilled in the art. In the same way the differential relays in the modified arrangements may be likewise graduated in a suitable manner to vary their speeds of operation.

Thus it will be seen that either with or without the precautions noted above the system of this invention is entirely operative either when one car approaches a signaling floor or when two or more cars simultaneously approach a signaling floor (which rarely occurs). In either case the signal circuit for one car will be completed and the signaling circuits for all other cars for that floor will be opened.

As car 2 approaches closer to the second floor, say when it is one floor or so away, a pair of brushes 56 and 57 will operate to close the circuit between contact 28 and strip 55. Contact 28 being connected to dynamo 1 as above described, current will flow through brushes 57 and 56, contact strip 55, wires 120, 121 and 122, car signal 4 in car 2, transfer switch 108 and wire 119 to the other side of the dynamo 1. Thus both the landing and car signals corresponding to car 2 are operated, while both of said signals for all other cars are arranged inoperative, so that in case another descending car enters the signal zone for the second floor, neither of such signals therefor will operate.

When the car which has caused operation of a landing signal (and of its car signal) in this manner passes beyond the signal zone for that landing, the connection between contacts 25 and 28 is interrupted and the windings 100 and 101 of the corresponding set of electro-magnetic intercontrolling devices are de-energized allowing the armature 96 which has been operated to return to normal position, thereby reestablishing the connection for the signal circuits at the intercontrolling devices for such signal circuits.

Upon such car passing out of the signal zone for this floor, the corresponding car-operated switch also operates to cause brushes 66 and 67 to close the circuit between contact 63 and strip 68, thereby causing current to flow in the restoring circuit of restoring magnet 43, causing the same to operate so as to lift arm 34 out of mercury pot 31 and break the circuit, thus restoring the system to its original inactive condition.

Generally speaking the operation of restoring the signals takes place in such manner that brushes 66 and 67 close the circuit between contacts 63 and strip 68 prior to the time connections between contacts 25 and 28 are broken, the object being to break the circuit in the mercury pot rather than break the circuit through the

brushes 47 and 48 passing off of contacts 25 and 28.

In case the operator of car 2, upon stopping at the second floor in answer to the above signal, finds that he cannot carry all the passengers waiting there, he can open switch 109 in the restoring circuit, so that when he leaves this floor, contact will remain closed at circuit breaker 31, while the interlocking devices of the corresponding set will all be returned to operative position with the result that the following car picks up the signals. In this case, however, the first car retains control of the signals, and prevents any other car from receiving or giving signals until such first car has left the landing.

The operator may, on the other hand, open transfer switch 108, thereby immediately cutting off the signals for his car, restoring the intercontrolling means to normal operative position, and thereby causing the signals to be picked up by another car already in the signal zone. Transfer of signals in this manner may be accomplished after the first car has stopped at the landing in case there is not sufficient room for all the passengers and the operator desires another car already in the zone to stop and pick up the remainder, or it may be accomplished before reaching the landing, in case the operator receives the signal to stop at a certain floor but does not wish to stop there, or wishes another car to also stop and assist in taking on the passengers. In case the operator does not wish to stop he may not only open the transfer switch 108 to transfer the signals to another car in the zone, but, before leaving the signal zone he can and should also open restoring circuit switch 109, so that in case his car leaves the signal zone before another enters such zone, the manually controlled break in the circuit at mercury pot 31 will remain closed, so that the next car entering the zone will pick up the signals.

The above description and operation of the signal system including my intercontrolling means applies to all intermediate floors, but in order to provide for operation of the signals at the top and bottom floors at the proper time, it will be observed that the commutator contacts and the inter-controlling means corresponding to each down signal at the top floor are located in the same series as those for the up signals at intermediate floors, while those for each up signal at the bottom floor are grouped with those for the down signals at intermediate floors. It will be also observed that in the normal operation of the elevator there is no need in the case of the top and bottom floors, of the manually controlled operation whereby a normally open break in the signal circuits is closed. There are therefore no main mercury pots or circuit closers for the signals at these floors, nor any setting and restoring magnets, so that such signals are adapted to always operate upon a car entering the signal zone. Push buttons 14 and 21 are, however, provided at the bottom and top floors respectively and are connected by wire 131, through a suitable resistance 93, to wire 129, wire 124 and thence to the battery 13. These push buttons normally have no function, but when the elevators are not in normal operation, for example, at night, switch 84 may be opened, and in such cases closing of any push button, including 14 and 21, will cause bell 94 to ring. These special provisions are also substantially the same as in the said Smalley and Reiners patent.

It will be seen that the system above described

provides means for automatically re-establishing the circuits to normal operating position, and so condition the circuits, so they will be receptive to function for subsequent signal operation. The 5 system also provides means whereby the transfer of signals between cars will be dependent upon the position of cars in relation to each other within the same zone. Assume that two cars are each just within the zone and successive push 10 buttons have been pushed, say two floors, in advance, the advanced car will be in control of the signals. On operation of transfer switch all the controlled signals will be transferred to the other car, cancellation is made of all signals in 15 control during effective operation of transferring means. In case the advanced car is say one floor in advance and in control of signals and transfer of signals is made, upon the normal restoration of transfer means, only the advanced 20 signal will be under control of the car in advance, the following car will assume control of the near signal.

In operation of the above system (Figs. 1-9) the circuit connections that function to establish 25 signal connections also function in disconnecting associated signal connections from their normal position. Furthermore anyone of the circuit connections on functioning to establish signal connections also functions to disconnect associated signal connections from normal operating 30 position.

One of the important embodiments of the invention is the electromagnetic feature utilized to 35 selectively control the operation of the signal circuits.

The operation of the signals is obtained through the resultant effort of two distinct features namely, first, the closing of a circuit signal connection through car movement means, followed 40 by an electromagnet circuit controlling means as a sequence operation, this second operation is dependent upon whether it is proper for this particular car to control the signal.

In the above described illustration of my invention the interlocking or intercontrolling of the signal circuits of the different cars is effected by means of electromagnets having opposed windings. It will be understood, however, that any electrically controlled device may be used 45 which operates upon control by any signal circuit connection to disable all the other signal operating circuits for that floor and direction of travel. Thus as shown in Fig. 10 each electromagnet device may comprise two windings 100 and 101 wound on different cores instead of on the same core, said windings being wound in opposition and operating upon a single armature 96 so that when both of said windings are energized 50 the armature is not operated and the circuit breaking device 97 and 98 connected to said armature is therefore left in closed condition. These windings 100 and 101 are connected in the same manner as above described so that winding 101 is connected in a branch circuit to the car operated switch, and therefore in the case when 100 is energized by reason of its series connections with the other electromagnetic devices of the set while winding 101 is not energized by reason of its connection to a car operated switch which has not closed contact, therefore, the armature 96 will be operated to break the circuit at 97 and 98, thereby disabling the corresponding signal circuit. Instead of the windings 100 and 101 being wound as in Fig. 10 55 they may be similarly wound, but operating on

opposite sides of the pivot of the armature 96 as shown in Fig. 11 so as to produce a similar result. In Fig. 12 I have shown an embodiment of my invention in which the contact arm 97 makes contact with a contact member on the core for the winding 101, and arm 97 being provided with a magnetic portion 96' so as to be held down by the action of winding 101 in case the same is energized at the same time as winding 100. In the case of any electromagnetic device 10 of this character which is connected to a car operated switch which is not yet in operation on account of the car not yet having entered the signal zone, energization of winding 100 by the control from another car will cause armature 96 15 to be operated, and the winding 101 not being energized, contact at 97 and 98 will be broken and corresponding signal circuits disabled for the time being.

In Fig. 13 I have illustrated a construction 20 of the electromagnetic intercontrolling devices consisting of a solenoid having windings 100 and 101 wound in opposition and operating upon a common core 96 which is connected to a contact member 97 normally establishing connection 25 between fixed contacts 98 and 98', the effect of winding 100 being to lift the core 96 and contact member 97 and interrupt the signal circuit at 98, 97, and 98' unless the winding 101 is energized at the same time and neutralizes the action 30 of winding 100 on the core.

As illustrated in Figs. 14 and 15 the intercontrol for the respective signal circuits for different cars may be provided for by mounting all the armatures 96 for the respective electromagnetic winding 100 on a common shaft 145, said shaft also having secured thereto a series of resilient spring contact members 97 adapted to cooperate with contact means on the core for the other winding 101 and provided with soft 40 iron armatures 96' whereby energization of winding 101 will hold the corresponding spring contact 97 down and maintain the contact at 97 and 98. Thus upon simultaneous energization of windings 100 and 101 which is effected in the 45 case of electromagnetic devices connected to a car operated switch of which the contacts have been closed by reason of the car coming into the signal zone, the corresponding signal circuit will be maintained in closed condition at contacts 97 50 and 98 but the signal circuits corresponding to that floor and direction of travel for all other cars will be interrupted by operation of the corresponding spring contact members 97.

In the forms of my invention shown in Figs. 55 16 and 17 each electromagnetic device comprises only a single electromagnet with one winding 146, the wire 106 from the contact arm of each device being connected near the middle of said winding as at 146'. In Fig. 16 each wire 102 60 from a main circuit closer is shown as connected by wires 147 and 148 to one end of the winding 146 of the electromagnetic device at each end of a set, all the electromagnets of the set being connected in series by wires 149. When 65 a signal circuit is established by the car operated switch for the car corresponding for example, to the bottom electromagnet in Fig. 16, the circuit through the set of electromagnets will be divided into two branches, one leading from wire 70 102 through wire 147, windings 146 of the top and intermediate electromagnets in series, wires 149, and one half of the winding of the bottom electromagnet to connection 146' for wire 106, and the other from wire 102 through wire 148 and 75

the other half of the winding of the bottom electromagnet to said connection 146'. The electromagnets corresponding to cars not in the signal zone will therefore be energized and attract their 5 armatures 96 and thereby break the corresponding circuits at 97 and 98, while the two halves of the winding of the bottom electromagnet will act in opposition to each other and the corresponding arm 97 will maintain connection with 10 contact 98 and thereby maintain the signal circuits for the proper car.

The construction and operation of the form 15 shown in Fig. 17 is similar to the above, except that wire 102 is connected to one end of the winding of each electromagnet in the set and said windings are all cross-connected at their other ends by wire 151, so that when a signal circuit is completed by any car-operated switch the current flows in parallel rather than in series 20 through the windings of all the electromagnets other than the one corresponding to the car in control.

In some cases it may be desired to provide 25 for electrically controlled means other than electromagnetic means for selectively controlling and interlocking the signal circuits. For example, as 30 shown in Fig. 18, electro-thermal means may be provided for this purpose. Referring to this figure, in which is shown a set of two devices of 35 this nature, wires 155 and 156 constituting electro-thermal elements, are supported at their upper ends at 157 and 158 and are attached at their lower ends to contact members 159 and 160, pivotally mounted as at 161. Wire 102 from the 40 corresponding main mercury pot or circuit closer, for example, 31, is connected to the upper end of wire 155 of a device at one end of a set, for example, the one at the left in Fig. 18. The lower end of this wire 155 is connected by wire 45 162 to the upper end of wire 155 of the next device, which in this case is at the other end of the set (there being only two devices in this set) but it is understood that the number of 50 such devices in a set will correspond to the number of elevator cars in the system, and that when this number is more than two, wires 55 162 will be provided to connect the lower end of each wire 155 to the upper end of the next one, so that all such wires are connected in series. Wire 155 of the end device to which wire 102 is 60 connected (and of all intermediate devices in a set of three or more) is insulated at its lower end from contact member 159 as indicated at 163, while wire 155 of the device at the other end of the set is electrically connected to its 65 contact member 159. All the contact members 159 are connected by wire 164. Wires 156 are all electrically connected to their contact members 160, while their upper ends are connected by wires 107 to the corresponding commutator 70 segments for example, segments 28 of their respective car-operated switches.

It is evident that, with the circuit closed at 31, if one of the car-operated switches makes contact between its segment 28 and the segment co-operated therewith, current will flow through all 75 the wires 155 in series and through wire 156 of the electro-thermal device corresponding to such switch. These wires are made of such fine wire as to be heated materially by the passage of the current and to therefore be elongated and permit their respective contact levers to fall. In the case of the device corresponding to the car which is in control of the circuits, both contacts 159 and 160 will fall equally and contact will be

maintained, while in all the other devices of the set, only contact 159 will fall as indicated in dotted lines in the right hand device, thereby breaking the connection and locking out these devices. When the connection at segment 28 is again broken by the car operated switch the wires will quickly cool off and return to their normal positions, again closing the contacts and placing all the devices in operative condition. 5

While I have shown push buttons or circuit closers at the landings as the initial means to control the signals, I do not wish to limit the scope of this invention to a definite sequence of operation wherein the push button operation always first occurs to primarily control the signals so they will be receptive to a completion of control by car movement, as in case of application of my invention to push button control elevator systems the push buttons or circuit closers call a car to the landing and the car which is responding to said call will selectively control the signals. In other words the elevator may be operable under direct control of passengears and it is desirable that the elevator shall selectively control or interlock the signals so duplication of signals will not be given. 10 15 20 25

My invention may also be applied, with some modification, to signal systems for so-called "department store" elevator systems, in which all the cars stop at each floor. The wiring circuits for such a system are shown diagrammatically in Fig. 19, in which the parts and connections are numbered, as far as possible, the same as in Fig. 1. It will be obvious that in such a system no push buttons are required at the landings and no car signals are required. The main mercury pots, with the setting and restoring magnets therefor, and the car-operated switch contact segments for the restoring magnets and for the car signals may therefore also be eliminated in such cases, together of course with the connections therefor. The other connections remain the same as in the other case, with the exception that wires 102' from the interconnecting devices, lead directly to wire 119 connected to the source of power 1. 40 45 The operation of the car-operated switches and of the intercontrolling means is the same in this case as in the other form, the result being in this case that whenever any car enters the signal zone corresponding to a certain floor, the landing signal for that car will be lighted, and the intercontrolling means will operate to break the circuits for all the other cars at that floor, so that no other car can signal at that floor until the first car has moved out of the signal zone. The 50 operator of any car, however, in case he does not wish to stop at a certain floor, may open transfer switch 108, thus breaking the circuit for his car so that the next car entering the zone or which may have already entered the zone subsequently 55 to the first car will give the signal at the landing. A distinctive feature of my invention, namely, the fact that the breaks in all the signal circuits at the inter-controlling means are normally closed, but upon the completion of the signal circuit for 60 any car, the intercontrolling means operates to open the breaks therein in the circuits for all the other cars, is the same in this embodiment of my invention as in the form first described. 65 70 75

I claim:

1. In an elevator signal system for a plurality of cars, individual landing signals for the cars, signal circuits for the respective cars, car controlled switch means individual to said cars for completing the landing signal circuit for the correspond- 75

ing car, and means operable upon the establishment of any one of the landing signal circuits to open all other landing signal circuits for that landing and to maintain said other circuits open 5 during the time such first circuit is maintained established.

2. In an elevator signal system for a plurality of cars, individual landing signals for the cars, signal circuits and car-controlled switches for the respective cars for completing the landing signal circuit for the corresponding car, normally closed means interposed in said signal circuits, interconnecting means between said car-controlled switches and said normally closed means, whereby when one of said signal circuits for any floor 10 is closed all other signal circuits for that floor are open.

3. In a signal system for a plurality of cars, individual landing signals for the cars, signal 20 circuits and car-controlled switches for the respective cars for completing the signal circuits for the corresponding car, and means operable upon the completion by a car-controlled switch of the circuits for any car for holding open the corresponding circuits for the other cars.

4. In an elevator signal system for a plurality of cars, individual car signals, circuits therefor, car-controlled switches for the respective cars for completing the signal circuits for the corresponding car, normally closed circuit-opening means interposed in the car signal circuits, means electrically interconnecting all of said circuit-opening means whereby upon establishment of any one of said car signal circuits, by one 30 of the car control switches the circuit opening means operate to open the corresponding signal circuits for all of the other cars and maintain said other circuits open while said one circuit remains established, said circuit-opening means 35 being also operable upon the breaking of said first circuit after establishment thereof to restore the circuit-opening means in all the other car signal circuits to normally closed position.

5. In an elevator signal system for a plurality of cars, individual landing signals, individual car signals, signal circuits for said landing signals and said car signals, a plurality of car-controlled switches corresponding to the respective cars, each of said switches controlling the closure of a 40 normally open break in the signal circuit corresponding to that car, electrically interconnected normally closed circuit-opening means also interposed in said signal circuits, said means being operable upon the establishment of a signal circuit corresponding to any one of said cars to open the corresponding landing signal circuits and car signal circuits for all the other cars and to maintain said circuits open while said first circuit remains established.

6. In an elevator signal system for a plurality of cars, individual landing signals, individual car signals, signal circuits for said landing signals

and said car signals, a plurality of car-controlled switches corresponding to the respective cars, each of said switches controlling the closure of a normally open break in the signal circuit corresponding to that car, electrically interconnected normally closed circuit-opening means also interposed in said signal circuits, said means being operable upon the establishment of a signal circuit corresponding to any one of said cars to open the corresponding landing signal circuits and car 10 signal circuits for all the other cars and to maintain said circuits open while said first circuit remains established, said circuit opening means being also operable upon the breaking of said first circuit after it is established to restore the circuit-opening means in the signal circuits corresponding to all the other cars to normally closed condition.

7. In an elevator signal system for a plurality of cars serving a plurality of floors, individual 20 signals for each of said cars for each floor, electric circuits including said signals, a car controlled switching means for each car operable in accordance with movements of the car for closing the circuit to the signals for that car for the floor 25 corresponding to the position of the car, and means operable by the establishment of the signal circuit for any floor for one car to open the signal circuits for all other cars for that floor 30 and to maintain said circuits open during the time such first circuit is established.

8. In an elevator signal system for a plurality of cars, each serving a plurality of floors, individual signals for each car for each floor, a circuit for each signal, means at each floor common 35 to the signals for all cars for that floor operable by a prospective passenger to prepare circuits to all signals for that floor, car controlled switching means for each car operable in accordance with movements of the car for completing the previously prepared circuits for that car upon approach of the car to a signaled floor, and means operable by the completion of the circuit for the signal of any car for any floor for opening the signal circuits for all other cars for that floor and 40 maintaining said circuits open during completion of said first circuit.

9. In an elevator signal system for a plurality of cars serving a plurality of floors, individual 50 signals for each of said cars for each floor, electric circuits for said signals, a car controlled switching means for each car operable in accordance with movements of the car for closing the circuit to the signals for that car for the floor corresponding to the position of the car, and magnetically operable switching means in said 55 circuits and operable by the establishment of the signal circuit for any floor for any car to render inoperative the signals of the other cars for that floor and to maintain said signals inoperative 60 during the time the first circuit is established.

ROBERT H. GAYLORD.
